CLAIM

The ornamental design for a carton, as shown and described.

DESCRIPTION

FIG. 1 is a perspective view of the carton showing my new design;

FIG. 2 is a bottom perspective view thereof;

FIG. 3 is a bottom plan view thereof;

FIG. 4 is a side elevation view of one of a pair of identical opposing sides thereof;

FIG. 5 is a top plan view thereof;

FIG. 6 is a side elevation view of one of a pair of identical opposing sides thereof; and,

FIG. 7 is a plan view of FIG. 1 shown in an unfolded condition.

The broken line showing in FIG. 7 represents fold lines only.
